UNITED STATES PATENT OFFICE.

JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

FURNACE RESISTOR MOUNTING.

Application filed November 28, 1923. Serial No. 877,560.

My invention relates to electrically heated furnaces and particularly to resistor mountings for electrically heated resistance furnaces.

5 The object of my invention is to provide a relatively simple resistor mounting for an electrically heated resistor furnace.

In practicing my invention, I provide a plurality of refractory heat-insulating walls 10 enclosing a furnace chamber. In one or more of such walls I mount a plurality of spaced sets of relatively thin, elongated, metal members, of substantially T-shape, projecting into the furnace chamber. The 15 metal members of T-shape are spaced laterally in each set and relatively thin refractory plates or bars, having lateral grooves in their inner surface, are held by the outer ends of pairs of members of T-shape. A relatively 20 heavy resistor member preformed to comprise a plurality of straight and substantially parallel-extending, end-connected convolutions is held by the grooved plates whereby the convolutions extend substantially 25 parallel to the furnace wall and closely adjacent thereto.

A substantially similar design is disclosed and claimed in co-pending application Serial No. 584,620 of T. A. Reid, filed August 28, 1922, and assigned to the Westinghouse Electric & Manufacturing Company. As set forth in that application, refractory members of T-shape are supported by the refractory walls of the furnace structure 30 and, in order to obtain sufficient strength, the lateral area of the members of T-shape are made relatively large and of such thickness as to be substantially equal to the thickness of the refractory bricks or blocks employed in building up the heat-insulating walls.

In the present invention, the metal members of T-shape are of such thickness that they may be placed between the respective layers of bricks or blocks and may occupy only such space as is usually occupied by the binding material employed to hold the successive layers of bricks in their proper operative positions in the respective walls.

45 50 In the single sheet of drawings,

Figure 1 is a view, in vertical lateral section, of an electrically heated furnace

comprising the device embodying my invention,

Fig. 2 is a view, in perspective, of a refractory grooved bar employed with the device embodying my invention,

Fig. 3 is a view, in perspective, of a device embodying my invention,

Fig. 4 is a view, in perspective, of a modified form of device embodying my invention, and

Fig. 5 is a view, in perspective, of a refractory bar employed with the modified form of metal supporting member illustrated in Fig. 4.

An electric furnace, designated generally by the numeral 11, comprises an outer casting 12, of a suitable heat-insulating refractory material usually employed in the art. 70 An inner lining 13 is composed of a plurality of bricks or blocks of a suitable high-temperature-resisting material, a number of co-operating walls being provided, suitably spaced apart to form or enclose a furnace 75 chamber 14 of any suitable or desired contour and dimensions.

The furnace structure is illustrated schematically only as the device embodying my invention may be employed with any similar 80 type of furnace comprising refractory walls occupying a plurality of bricks or blocks in the inner lining.

A plurality of spaced sets of relatively thin and elongated metal members 15, of substantially T-shape, are provided in one or more of the walls of the furnace structure 11. The members 15 are illustrated more particularly in Fig. 3 of the drawing, and comprise a relatively narrow, thin, and 90 elongated main portion 16 and an integral flange portion 17 at one end thereof. The thickness of the main portion 16 is such that it may be placed between two successive layers of bricks or blocks comprising the inner 95 lining 13, the binding material usually provided being omitted where the member 15 of T-shape is located.

The members 15 in the respective sets are spaced apart a suitable distance, and relatively narrow bars 18, of a suitable refractory electric-insulating material, extend between spaced pairs of members 15. Each of the members 18 is provided, in one face

thereof, with a plurality of spaced and laterally-extending grooves 19 and that face of the member 18 which is provided with the grooves 19 is normally located closely adjacent to a surface of the wall supporting the members 15.

A resistor member 21 of relatively heavy metal, preformed to comprise a plurality of straight and substantially parallel-extending convolutions, has parts of the individual convolutions located in the respective grooves 19 to extend therethrough and between the members 18 supported by the spaced sets of members 15, substantially as illustrated in Fig. 1 of the drawing.

The end portions of the respective resistor members 21 are bent at substantially right angles to the plane of the convolutions and may extend through suitable insulating bushings 22 provided in the respective walls of the furnace structure.

In mounting the individual resistor members 21 in their proper operative positions in the furnace structure, they are moved in a direction substantially at right angles to the plane of the convolutions and of the adjacent furnace wall so that the end portions will extend through the bushing 22 and the individual convolutions will be held temporarily by the operator in substantially their proper operative positions. The bars 18 may then be placed in their proper operative positions with a part of each convolution located in a groove 19, the bars 18 being temporarily located out of contact with the co-operating supporting members 15 and moved into their proper operative positions longitudinally of the convolutions.

As the resistor member 21 expands and contracts during the normal operation of the furnace, it is necessary to provide means to prevent movement of the members 18 away from the supporting members 15, and I provide relatively small key members 23 that are located on the respective sides of the members 18 and extend through suitable openings 24 in the members 15, closely adjacent to the flange portion 17.

In Fig. 4, I have illustrated a modified form of metal member 25 that is provided with a single opening adjacent the outer end through which extends a locking pin 26 that is easily and quickly removed therefrom.

A refractory bar 27, having a plurality of laterally-extending grooves 19 in one surface thereof, is provided with longitudinally extending grooves 28 in that face opposite to the grooved face at each end of the bar. The longitudinal extent of the grooves 28 is sufficient to permit of inserting and removing the holding pin 26 which has its ends located in the grooves 28 of the two members 27 operatively engaging any one of the members 25.

When the modification of the metal supporting member, illustrated in Fig. 4, is employed, the method of assembly is slightly different from that described when member 15 is employed in that, after the resistor member 21 has been placed temporarily closely adjacent to one of the walls, the respective bars 27 may be placed in their proper operative positions by being moved toward the surface of the wall, it being understood that the pins 26 have been removed from their normal operative positions in the members 25. After the bars 27 have been placed in their proper operative positions closely adjacent to the co-operating furnace wall and supported by, and extending between, the members 15, the holding or locking pins 26 may be dropped into their proper operative positions, thereby preventing any lateral movement of the bars 27 away from the supporting members 15.

As furnaces of the type referred to in this application are intended to operate at relatively high temperatures, I employ metal members 15 or 25 that are made of a metal that does not oxidize at such relatively high temperatures and I may employ nichrome or some similar material for this purpose.

As the distance between pairs of members 15 in the respective sets thereof cannot be made very large, on account of the strength of the members 18 and 27, the weight that each member 15 must support is relatively small and, as the overhang thereof or the distance which it projects into the furnace chamber may be made relatively small, the thickness of the main portion 16 may be made relatively very small, thereby permitting, as was hereinbefore stated, the insertion of this member in place of the binding material provided to hold the adjacent layers of bricks or blocks together.

The device embodying my invention thus permits of covering a much greater portion of the furnace walls with a resistor member than would be the case if the supporting members of T-shape were made of relatively thick refractory material, as has heretofore been the case. As the grooved refractory bars may be made relatively narrow, substantially all of the resistor member 21 is left bare and in direct heat-radiating relation within the furnace chamber, thereby preventing any pocketing of the heat and possible damage to the resistor.

Various modifications and changes may be made without departing from the spirit and scope of the invention, and I desire, therefore, that only such limitations shall be placed thereon as are imposed by the prior art.

I claim as my invention:

In an electric furnace, in combination, a refractory wall, a plurality of spaced pair of relatively thin metal members, of sub-

stantially T-shape, and of substantially non-
oxidizable material, supported by said wall
and projecting therefrom, a notched refrac-
tory bar, of electric-insulating material ex-
tending between each pair of metal mem-
bers, a resistor member supported by said
notched refractory bars and being substan-
tially self-supporting therebetween, and

means operatively associated with each mem-
ber of T-shape for preventing movement of 10
said bars laterally thereof.

In testimony whereof, I have hereunto
subscribed my name this 20th day of Novem-
ber, 1922.

JAMES C. WOODSON.
